UNITED STATES PATENT OFFICE.

KATHERINE CORRISTON, OF WESTERLEIGH, NEW YORK, ASSIGNOR TO WILLIAM S. SWIFT, OF NEW YORK, N. Y.

REVOLVER HOLSTER.

Application filed February 7, 1925. Serial No. 7,504.

This invention relates to revolver holsters, and has for its primary object to provide a simple and inexpensive means automatically operating to lock the revolver in the holster and prevent its accidental loss therefrom.

More particularly, my present improvements provide such a guard device for revolver holsters, which is so constructed and arranged that the very quick withdrawal of the revolver from the holster is permitted.

It is a further general object of the invention to provide a device of the above kind, which may be readily applied to any ordinary leather revolver holster and the several parts of which may be very inexpensively produced in the form of metal stampings.

With the above and other objects in view the invention consists in the improved revolver holsters and in the form, construction and arrangement of the several parts as will be hereinafter more fully described, illustrated in the accompanying drawings and subsequently incorporated in the subjoined claims.

In the drawing wherein I have illustrated one simple and practical embodiment of the invention and in which similar reference characters designate corresponding parts throughout the several views—

Figure 1 is a rear elevation of the revolver holster provided with my present improvements,

Figure 2 is a vertical sectional view taken on the line 2—2 of Figure 1,

Figure 3 is a horizontal section taken on the line 3—3 of Figure 1, and

Figure 4 is a detail perspective view of the latch element.

Referring in detail to the drawings wherein I have illustrated a holster of conventional form, the holster body 5 may be formed of heavy leather or other suitable material, cut to proper shape, and then bent to provide a relatively wide upper section 6, open at its rear side, and a tapering or contracted lower section 7, which is closed at the rear side thereof. It is understood, of course, that the central or intermediate portion of the leather holster closes both of these upper and lower sections at their front sides.

When the revolver, indicated at R, is inserted in the holster, the barrel thereof is

received in the lower section 7 of the holster, while the body in which the revolver barrel is mounted, occupies the upper section 6 of the holster, the trigger guard, shown at G, projecting rearwardly through the open side thereof.

My present improvements, in one practical embodiment thereof, consist essentially in a plate 8, preferably of sheet metal bridging the rear open side of the section 6 of the holster. This plate is preferably bent or stamped into substantially U-shape form to provide spaced end portions 9 to extend upon the outer faces of the side walls of the sections 6 of the holster. These end portions of the plate may be permanently secured in any approved manner to the holster walls, as, for instance, by the rivets 10.

The intermediate portion of the plate 8, bridging the space between the side walls of the holster section 6 at their rear edges, is provided with a vertically extending recess 11 opening upon the upper edge of said plate and terminating in spaced relation to the lower edge thereof, to provide a seat 12 for the trigger guard G of the revolver. At one side of this seat, the edge of the recess 11 is curved upwardly and outwardly, as at 13, to one of the end flanges 9. At the opposite side of the seat 12, the intermediate portion of the plate is provided with an outwardly projecting flange 14, the purpose of which will hereinafter become apparent.

In the plate 8 below the seat 12, a stud 15 is fixed and projects inwardly from said plate. A latch lever 16 is loosely mounted upon the inner end of this stud for pivotal movement and a suitable spacing washer is interposed between said lever and the plate 8. Above the stud 15, the latch lever terminates in a hook 18, positioned in a plane substantially parallel to the plate 8, the lower edge 19 of said hook being spaced above the seat 12. The hook 18 is provided with an upper inclined cam edge 20. As seen in Figure 1 of the drawings, in the normal position of the lever 16, the bill of the hook 18 projects across the recess 11 from the flange 14 towards the curved edge 13 of the plate 8. The latch lever is normally held yielding in such position by means of a suitable leaf spring 21, one end of which is riveted to the inner side of one end portion 9 of the plate. This spring extends downwardly from its fixed end and

the free end thereof is curved and has bearing pressure against the curved edge 22 of the lever 16.

The latch lever 16 is provided at its lower end with an angularly disposed rearwardly projecting finger piece 23. Movement of the lever under the action of the spring 21 is limited by a suitable stop pin 24 fixed in the plate 8.

10 In the use of the device above described, it will be understood that when the revolver is inserted into the holster, the trigger guard G projecting from the rear side thereof, readily enters the upper flaring end of the 15 recess 11, and by contact, either with the cam edge 13 or the flange 14, is directed upon the upper inclined cam edge 20 of the lever 16, thereby rocking this lever upon the pivot stud 15 to the position 20 indicated in dotted lines in Figure 1 of the drawings, so that the lower side of the trigger guard may engage upon the seat 12. When the guard is so positioned, the spring 21 returns the lever 16 to normal position, 25 thereby engaging the hook 18 of said lever over the lower portion of the trigger guard, to securely retain said guard upon the seat 12. Thus, no amount of agitation will result 30 in an upward movement of the revolver in the holster, whereby it might become entirely displaced therefrom and lost. The lower curved edge 19 of the hook will prevent the upward movement of the guard in the recess 11, even though the spring 21 may eventually become considerably weakened.

Notwithstanding the provision of such a safety guard for the revolver, the latter may be quickly withdrawn or removed from the holster by simply engaging one of the fingers, when grasping the revolver with the finger piece 23 and applying pressure thereto against the action of spring 21. Upon thus disengaging the hook 18 with the trigger guard, the upward and outward movement of the revolver from the holster is permitted.

From the foregoing description considered in connection with the accompanying drawings, the construction manner of operation and several advantages of my present improvements will be clearly and fully understood. It will be seen that I have devised a very simple, inexpensive and effective safety guard for revolver holsters and one 55 which may be readily applied to such holsters as are now in common use. I have herein shown a desired form of the bridge plate 8 upon which the latch means engaging the trigger guard is mounted, but it will be 60 understood that this bridge plate may be produced in various other forms as may be

required, by the particular size or shape of the holster. Further, the several detail parts of the guard means may also be susceptible of considerable modification and I therefore reserve the privilege of resorting to all such legitimate changes as may be fairly embodied within the spirit and scope of the invention as claimed.

I claim:

1. A revolver holster having a lower pocket like section containing the free end of the barrel; an upper half open, or winged section embracing the main body of the revolver, but leaving the handle free; a plate 75 bridging the ends of the wings of the said upper section, and having a recess towards the open end of the holster for receiving the trigger guard and a seat for said trigger guard at the bottom of the recess; and 80 spring pressed latch means pivotally mounted upon said bridge plate for engagement over the trigger guard to retain the same on the said seat.

2. A revolver holster having an upper section open at its rear side, a plate fixed to the side walls of said holster section and bridging the rear open side thereof, said plate having a vertical recess open at its upper end to receive the trigger guard of a 90 revolver and provided at its lower end with a seat for said guard, a latch lever pivotally mounted upon the inner side of said bridge plate having an outwardly projecting finger piece at its lower end and formed 95 with a hook at its upper end, a leaf spring engaging one edge of said lever and acting to retain the hooked end thereof in engagement over the trigger guard, and a stop fixed in said bridge plate and limiting the pivotal 100 movement of said lever to the latter position.

3. A revolver holster having an upper section open at its rear side, a plate bridging the open side of said holster section and provided with a vertically extending recess opening upon the upper edge thereof and having a seat at its lower end for the trigger guard of a revolver, said plate at one side of said recess being provided with an 105 upwardly and outwardly curved cam edge and having an outwardly projecting flange at the opposite side of the recess disposed in a plane at right angles to the plane of said plate, and manually operable spring pressed 110 latch means upon the inner side of the bridge plate to engage the trigger guard and retain the same upon said seat.

In testimony that I claim the foregoing as my invention, I have signed my name 115 hereto.

KATHERINE CORRISTON.
